CLAIM

The ornamental design for a filter cartridge as shown and described.

DESCRIPTION

FIG. 1 is a perspective view of a filter cartridge according to a first embodiment.

FIG. 2 is a first side elevation view of the filter cartridge of FIG. 1.

FIG. 3 is a second side elevation view of the filter cartridge of FIG. 1.

FIG. 4 is a third side elevation view of the filter cartridge of FIG. 1.

FIG. 5 is a fourth side elevation view of the filter cartridge of FIG. 1.

FIG. 6 is a first end view of the filter cartridge of FIG. 1, which in at least some configurations may be a top plan view.

FIG. 7 is a second end view of the filter cartridge of FIG. 1, which in at least some configurations may be a bottom plan view.

FIG. 8 is a perspective view of a filter cartridge according to a second embodiment.

FIG. 9 is a first side elevation view of the filter cartridge of FIG. 8.

FIG. 10 is a second side elevation view of the filter cartridge of FIG. 8.

FIG. 11 is a third side elevation view of the filter cartridge of FIG. 8.

FIG. 12 is a fourth side elevation view of the filter cartridge of FIG. 8.

FIG. 13 is a first end view of the filter cartridge of FIG. 8, which in at least some configurations may be a top plan view.

FIG. 14 is a second end view of the filter cartridge of FIG. 8, which in at least some configurations may be a bottom plan view.

FIG. 15 is a perspective view of a filter cartridge according to a third embodiment and having an indeterminate length.

FIG. 16 is a first side elevation view of the filter cartridge of FIG. 15.

FIG. 17 is a second side elevation view of the filter cartridge of FIG. 15.

FIG. 18 is a third side elevation view of the filter cartridge of FIG. 15.

FIG. 19 is a fourth side elevation view of the filter cartridge of FIG. 15.

FIG. 20 is a first end view of the filter cartridge of FIG. 15, which in at least some configurations may be a top plan view; and,

FIG. 21 is a second end view of the filter cartridge of FIG. 15, which in at least some configurations may be a bottom plan view.

The dash-dash broken lines in the drawings illustrate portions of the filter cartridge that form no part of the claimed design. The dash-dot broken lines in the drawings illustrate boundaries and form no part of the claimed design.
